FIG. 1.

The characteristic feature of my design resides in the particular Earth and spaceship representations in combination with the toy spinning top, as shown.

I claim:

The ornamental design for a toy spinning top, as shown and described.
